UNITED STATES PATENT OFFICE.

LESLIE HURST BURROWS, OF HOBART, TASMANIA, AUSTRALIA.

MANUFACTURE OF BOOTS AND SHOES.

Application filed January 16, 1923. Serial No. 612,948.

To all whom it may concern:

Be it known that I, LESLIE HURST BURROWS, a subject of the King of Great Britain, residing at Hobart, in the State of Tasmania, Commonwealth of Australia, have invented certain new and useful Improvements in and Connected with the Manufacture of Boots and Shoes, of which the following is a specification.

10 This invention relates to the manufacture of footwear such as boots and shoes and particularly to the mode of securing the soles thereto and in mending the same.

In repairing boots and shoes the existing 15 method requires skilled labor and also tends to mutilate the insole and boot upper, when nails or rivets are used, and it is to avoid such happening and to simplify the repair work that this invention has been devised.

20 According to the invention, specially prepared welt and outer soles are provided together with a fastening means for connecting same together. The same fastening will be used for the lowest lift of the heels, the 25 head of which can be removed when a worn sole or part of the heel is to be replaced. But in order to fully understand the invention reference is made to the accompanying drawings, in which

30 Fig. 1 is a plan, from below, of the heel and sole with fastenings.

Fig. 2 shows in transverse section a boot upper and the soles attached.

Fig. 3 is a like view across the heel.

35 Fig. 4 illustrates in longitudinal section a boot constructed according to this invention.

Fig. 5 is a perspective view of the female member of the fastening, Fig. 5½ is a sectional view of the same, and

40 Fig. 6 is an elevation of the bifurcated holding member of the same.

The boot upper 7 is made in the usual way with an insole 8 over which is a sock 9. The welt sole 10 is riveted or is otherwise attached to the insole in the ordinary manner, but is provided with holes around the edges of the sole countersunk on the inside surface next the insole. In these holes the female member 11 of the fastening is placed.

45 Placed over the welt sole is the outer half sole 12 that is provided with openings co-

incident with those in the welt sole but countersunk on the outer side. In these openings the male member 13 of the fastening is placed.

55 Referring to the fastening, the part 11 is hollow with a conical centre forming an anvil or spreader 14, so that, when the bifurcated member 13 is inserted in the opening and driven home, its points will be spread 60 outwards by the cone and the parts will lock. By means of the countersunk openings on the inner side of the welt sole and the same on the outer side of the half sole 12 each part of the fastening is conveniently and securely 65 housed and the two soles will be satisfactorily held together when the parts 13 are driven in. The male member may, if desirable, be made to screw into the part 11 for which purpose each would be provided with 70 a thread.

When the half sole wears it can be replaced by another after removing the rivet 13 which, it will be noticed, is contained within the part 11 and thus when removed 75 does not injure the leather. The head 13 can be quickly separated from the socket 11 by placing a small lever under the head while the other part remains in the welt sole.

The heel is treated in the same manner, 80 the lifts of same being held together in the usual way except that the last or wearing lift is perforated and countersunk on the outside and the lift next above similarly treated and countersunk upon the inside surface to retain the socket member 11 into which the rivet 13 is locked through the lowest lift, 85 thus holding the same to the heel. Under the sock 9 and over the heel I place a piece of rubber 15 shaped to the inside of the boot or shoe, in order to impart resiliency to the same.

90 Thus, it will be possible to attach an outer or walking sole, or to replace a worn sole on a shoe, in an extremely simple manner and 95 without special knowledge. The countersinkings in the outer sole are deep enough to entirely receive the heads of the rivets.

Having now described my invention what I claim as new and desire to secure by Letters Patent is—

A boot or shoe having a welt sole secured

to the insole, and provided with countersinks on the inside surface thereof, an outer half sole, having on its outer surface countersinks coincident with those in the welt sole, a hollow socket piece having a central cone or spreader in each countersunk opening in the welt sole and a bifurcated rivet

that passes through the outer sole and is driven into the hollow socket and is recessed in one of the countersinks of the outer half sole.¹⁰

In witness whereof I affix my signature.

LESLIE HURST BURROWS.
